UNITED STATES PATENT OFFICE.

CHARLES A. WICKSTROM, OF CHICAGO, ILLINOIS, ASSIGNOR TO WESTERN ELECTRIC COMPANY, INCORPORATED, OF NEW YORK, N. Y., A CORPORATION OF NEW YORK.

POLISHING-MACHINE.

1,376,663.

Specification of Letters Patent.

Patented May 3, 1921.

Application filed March 28, 1918. Serial No. 225,234.

To all whom it may concern:

Be it known that I, CHARLES A. WICKSTROM, a citizen of the United States, residing at Chicago, in the county of Cook and State of Illinois, have invented certain new and useful Improvements in Polishing-Machines, of which the following is a full, clear, concise, and exact description.

This invention relates to polishing machines, and more particularly to a machine for polishing flat surfaces.

The object of this invention in general is to provide a compact, easily accessible, and convenient machine for rapidly and thoroughly polishing flat surfaced articles without the aid of skilled operators.

In accordance with one feature of this invention there is provided a mechanism adapted to be mounted on a bench with the working or polishing surface and work holding mechanism conveniently located above the bench while the operating mechanism and supporting structure is located below the bench. The supporting structure 25 preferably comprises two separable members adapted to house and support the operating mechanism and is provided with means for conveniently securing the apparatus to the bench.

Another feature of this invention relates to an improved work holding device, by means of which a plurality of similar articles, the faces of which are to be polished, may be held in operative relation to the 35 polishing surface with a uniform pressure regardless of allowable manufacturing variations in the sizes of the parts. This mechanism may comprise a main holder supplied with a plurality of individual holders each 40 of which is provided with spring controlled clamping elements which coöperate to maintain a uniform pressure upon each of the devices to be polished.

Other features of the invention relate to 45 the specific details of construction of the work holding clamps, and to other details of construction and combination of parts as will hereinafter more fully appear.

In the drawings illustrating this invention—

Figure 1 is a plan view of the mechanism embodying the invention;

Fig. 2 is a view in side elevation of the device;

Fig. 3 is a transverse sectional view taken 55 upon the line 3—3 of Fig. 1;

Fig. 4 is a longitudinal sectional view taken upon line 4—4 of Fig. 1;

Fig. 5 is a plan view of the device with a portion removed showing the driving 60 mechanism;

Fig. 6 is a detailed sectional view illustrating one position of the polishing surface clamping device;

Fig. 7 is a plan view of a jack strip upon 65 which the device of this invention is adapted to operate, and

Fig. 8 is a view in front elevation of the device shown in Fig. 7.

As shown in the drawings, 5 and 6 designate upper and lower base members which are adapted to be secured together in any suitable manner and to be secured to the lower face of a bench top 7, as shown in Fig. 3, with the polishing surface and work 75 holding means extending through an opening 8 in the bench top.

A polishing surface 10, which may be emery cloth or any other similar material, is secured to a supporting plate 11 which is 80 mounted to reciprocate longitudinally in a frame 12 which is reciprocally mounted in guides or ways 13, 13 in the upper frame member 5.

Secured to the lower frame member 6 is a 85 suitable driving device such as the motor 15 which is connected through a worm 16 and gear 17 to a shaft 18 located within a housing or bearing 14 secured to the lower frame member 6. Mounted upon the upper end of 90 the shaft 18 within the base member 6 is a gear wheel 19 meshing with a second gear wheel 20 carried by a shaft 21 and secured to a fly wheel or inertia member 22 by means of screws 23, 23. Carried by the gear wheel 95 20 is an eccentrically mounted pin 25, to one end of which is connected the crank arm 26, the other end of which is pivotally secured to the supporting plate 11. The supporting plate is thereby reciprocated by the crank 100 arm 26 through the rotation of the gear wheel 20.

Mounted upon the lower end of the shaft 21 is a pinion 30 meshing with a gear wheel

31 supported upon a shaft 32 below the frame member 6. This gear wheel 31 drives an eccentric rod 35, one end of which is attached to a reciprocating link 36, the other end of which link is connected with a pivotal link 37 secured to a rock shaft 38 having its upper end secured to projecting lugs 39, 39 projecting from the transversely reciprocating plate 12. On its end opposite to 10 the link 37 the rock shaft 38 also carries a link 41, the upper end of which is also attached to the plate 12. The gear combination is preferably such that the plate 12 will be reciprocated at about one fourth the rate 15 of the plate 11.

The work supporting means consists in general of a main rectangular frame 50 pivotally supported at one end by means of a shaft 51 carried in lugs 52, 52 upon the 20 upper base member 5. A counter-balancing spring 53 surrounds the shaft 51 and engages the end of the frame member 50 in a manner to tend to swing the free end of said frame in an upward direction. At its free 25 end the frame 50 is provided with a handle 56, by means of which the frame 50 may be raised and lowered, and a spring operated trigger 57 is adapted to catch and retain the free end of said frame to support the work 30 in operative position to the polishing surface. Between the ends of the frame member 50 are two transversely arranged rows 60 and 61 of clamping lugs each comprising a pivotally supported lever 62 provided on one side with a projecting lug 63 adapted 35 to engage a piece of work 64. Each lever is also provided with a projecting finger member 65 adapted to rest upon one end of a coiled spring 66, the other end of which 40 rests upon the frame member 50. Secured to each of the levers 62 is a crank arm 67. The crank arms of oppositely disposed clamping lugs are connected by means of a bar 68 which engages the crank arms 67 45 of one row of clamps upon the upper side of their pivots and the other crank arms 67 of the other row of clamps upon the lower side of their pivots. Each crank arm of one row of clamping means is provided with 50 an upwardly extending operating lever or handle 70, the operation of which serves to rotate the clamping means 60, 61 of the two rows to engage and disengage the work. This handle or lever extends upwardly 55 through openings 71, 71 between sheet metal shields 72, 72 and is adapted to be swung laterally into a locking notch 73 to retain the work clamping means in a locked position. Leaf springs 75, 75 are adapted to engage 60 the article to be polished upon the side of a projecting lug or ear 76 opposite to that which is engaged by the clamping lugs 63, 63 to lift the work from the polishing surface when the pressure of the clamping 65 lugs 63, 63 is removed. A work holding de-

vice as constructed is capable of carrying a plurality of similar articles to be polished and to insure that each of the articles will be held against the polishing surface with a sufficient pressure to insure the proper polishing thereof regardless of manufacturing variations in the dimensions of the articles. 70

Clamping means for securing the polishing surface 10 to the supporting plate 11 comprises a stationary clamp member 80 75 consisting of a movable plate 81 adapted to be moved toward and away from the supporting plate 11 by means of an eccentric nut 82. An adjustable clamping means comprising a movable plate 83 carried by a movable bracket member 84 is adjustable with respect thereto through the agency of an eccentric nut 85, and the member 84 is adjustable with respect to the plate 11 through the agency of a clamping bolt 86. 80

By the construction and combination of parts whereby the polishing mechanism may be located out of the way below the bench top with only the polishing surface and article clamping means exposed above the bench, there is obtained an economy of space and a very convenient and safe arrangement for the operator, since no moving parts other than the polishing surface are exposed to the operator. 90

What is claimed is:

1. In a machine for polishing flat surfaced articles, the combination with a bench top provided with an opening therefor, of a polishing surface extending through said opening, and operating mechanism for said polishing surface located below said bench top and secured thereto. 95
2. In a polishing machine, a polishing surface, operating mechanism for moving said surface with a constantly changing direction of movement, separable supporting members for housing and supporting said operating mechanism and said polishing surface, a bench top, and means for securing said machine to the bench top. 105
3. In a polishing machine, the combination with a polishing surface and an article to be polished, of spring pressed clamping means adapted to engage opposite ends of the article to be polished and an operative connection between the clamping means at opposite ends of said article. 115
4. In a polishing machine, a polishing surface and a work holding device including a plurality of individual article holding devices each comprising a pair of oppositely located spring pressed clamping members and an operative connection between the clamping members of each pair. 120
5. In a polishing machine, the combination with a polishing surface and an article to be polished, of spring pressed clamping means adapted to engage opposite ends of the article to be polished, means connecting 125
- 130

said clamping means at opposite ends of said article adapted upon operation to operate said clamping means, and means located at one end of the article to be polished for 5 operating said connecting means.

6. In a polishing machine, the combination with a polishing surface and an article to be polished, of spring pressed clamping means at opposite ends of the article to be 10 polished adapted to engage the article there-

at, a crank arm secured to each of said clamping means, a bar connecting said crank arms, and an operating handle secured to one of said crank arms whereby both of said clamping means are operated simultaneously. 15

In witness whereof, I hereunto subscribe my name this 7th day of March A. D., 1918.

CHARLES A. WICKSTROM.
